UNITED STATES PATENT OFFICE.

WALTER NORTHCOTE NAYLOR, OF FOREST HILL, AND STANLEY PAGE HUTTON, OF BECKENHAM, ENGLAND.

APPARATUS FOR THE MANUFACTURE OF METALLIC ALLOYS.

1,132,376.

Specification of Letters Patent. Patented Mar. 16, 1915.

Original application filed November 22, 1912, Serial No. 732,972. Divided and this application filed March 7, 1913. Serial No. 753,138.

To all whom it may concern:

Be it known that we, WALTER NORTHCOTE NAYLOR and STANLEY PAGE HUTTON, citizens of the United Kingdom of Great Britain and Ireland, and residents of 169 Stanstead road, Forest Hill, in the county of London, England, and 30 Manor road, Beckenham, in the county of Kent, England, respectively, have invented certain new and useful Improvements in Apparatus for the Manufacture of Metallic Alloys, of which the following is a specification, such as will enable others skilled in the art to which it appertains to make and use the same.

This invention relates to apparatus for the manufacture of metallic alloys, such for example as that described in our application for United States Patent Serial No. 732,972 of November 22nd, 1912, of which this application is a division.

In the accompanying drawings, Figure 1 shows the apparatus together with a crucible.

In using this a quantity of aluminium is melted in a crucible *a* and to this is added at a temperature of about 600° C. or thereabout a percentage of magnesium and phosphor tin. The magnesium and phosphorated tin are incorporated with the aluminium by means of a special device in the form of a tube or casing *b* through which the magnesium is made to enter the molten aluminium at the bottom of the crucible, this method being adopted owing to the low melting point and specific gravity of the magnesium.

The tube or casing *b* is cylindrical and open at its lower end and it is fitted with a plunger or piston *c* and sliding rod *d* of which passes up through the tube and extends for a considerable distance beyond the same.

In use the tube *b* is charged with pieces or blocks of magnesium *e* and with pieces of phosphorated tin *f* placed in between. The sliding rod is drawn out as shown to the left of the figure for the purpose of charging the tube and a suitable wad of paper or other fabric *g* is placed between the end of the piston and the hole through which the rod slides. The open end of the tube is now blocked with a wad so as to keep it in place. At the required time the tube charged as described, is thrust with its open end down-

ward into the molten aluminium. The contained magnesium and phosphor tin are quickly melted out and flow into and mix with the aluminium in the crucible, the weight of the plunger or sliding rod *d* assists in forcing out the contents of the tube as it descends, and the position of the said rod serves to indicate when the metal has been properly melted out and diffused. The molten metal thus mixed may be suitably stirred with a carbon stick or in other suitable manner to insure a thorough incorporation of the magnesium with the aluminium.

The upper end of the sliding rod *d* may be fitted with a smaller bell-shaped cavity or cup *h* whereby any further addition of small quantities of phosphorus may be made by wrapping a piece of phosphorus in tin foil and inserting it in the said cup, the cup being then plunged into the molten metal. The small cup *h* may if required be made as a separate tool at the end of a rod.

Fig. 2 of the drawings shows a modified form of the improved device wherein a shallow bell-shaped casing *b* is provided and fitted with a piston *c* having an extended rod as before described. With this construction a substantially large block of metal may be dealt with as indicated instead of small pieces as in Fig. 1. A removable cross-bar *j* is provided for keeping the blocks of metal in place until melted.

What we claim and desire to secure by Letters Patent is:

1. In combination, a tubular chamber; a piston therein; and soft wadding disposed within one end of the chamber, engaging the sides thereof at points within the chamber remote from said end, for holding material in the chamber, said chamber being free from obstructions in its middle part, whereby cylindrical pieces of material may be held therein.

2. An apparatus for adding magnesium and phosphor tin to molten aluminium, said apparatus comprising, in combination, a tubular chamber open at its lower end, having a perforated closure at its upper end and having its intermediate part adapted to be filled with solid material having a diameter approximating the inner diameter of the chamber; a plunger movable within the chamber; an indicating rod attached to and

movable with the plunger and passing through the perforation of the closure; and means disposed within the lower end of the chamber engaging the sides thereof away from said end, and free from projections into the intermediate part of the chamber, and adapted to hold said material in the chamber when the material is solid.

In witness whereof we have hereunto set our hands in presence of two witnesses.

WALTER NORTHCOTE NAYLOR.
STANLEY PAGE HUTTON.
